ELECTRICAL RESISTOR

George E. Megow, South Milwaukee, Wis., assignor to Allen-Bradley Company, Milwaukee, Wis., a corporation of Wisconsin

Application July 18, 1936, Serial No. 91,305

1 Claim. (Cl. 201—63)

This invention relates to electrical resistor units and refers particularly to fixed resistor units used in radio circuits and especially radio receivers.

5 Fixed resistors of this type now generally consist of a molded or lumped body of resistance material with wire leads projecting from the ends thereof by which the unit is connected in the circuit.

10 Modern radio receivers and particularly those for use in automobiles, have their composite elements compacted into small space and the trend is to even greater compactness. Obviously, crowding the parts together in this manner entails special provision for electrical insulation as the clearances between the different parts is ordinarily inadequate.

15 In keeping with this growing necessity for positive electrical insulation, it is an object of this invention to provide a simple efficient manner of insulating fixed resistor units of the character described.

20 Resistor units of this type are color coded to indicate their different values and generally the color code marking is applied directly to the body 25 of the unit. This marking should be visible at all times and consequently, it is another object of this invention to provide an insulation for resistor units of the character described which is transparent so as not to conceal the color code marking.

25 A further object of this invention is to provide means for insulating resistor units which affords a degree of protection against moisture 30 and which adds to the mechanical strength of the unit and provides protection against obliteration of the color code marking.

35 While adequate insulation and transparency are of primary importance, low cost is also an 40 important consideration, and consequently it is another object of this invention to provide an insulating enclosure for lumped resistor which is made of inexpensive material easily formed and applied.

45 With the above and other objects in view which will appear as the description proceeds, this invention resides in the novel construction, combination and arrangement of parts substantially as hereinafter described and more particularly defined by the appended claim, it being understood that such changes in the precise embodiment of the herein disclosed invention may be made as come within the scope of the claim.

50 The accompanying drawing illustrates seven 55 complete examples of the physical embodiment

of the invention constructed according to the best modes so far devised for the practical application of the principles thereof, and in which:

Figures 1 to 7, inclusive, are perspective views 5 of resistor units illustrating several different embodiments of this invention;

Figure 8 is a cross section view through Figure 1, on the plane of the line 8—8; and

Figure 9 is a cross section view through Figure 4, on the plane of the line 9—9. 10

Referring now particularly to the accompanying drawing, the numeral 5 designates the body of a lumped resistor unit which is preferably cylindrical with an outer cylindrical wall 6 and end walls 7. Projecting from the ends of the 15 body are wire leads 8 by which the unit is connected in an electrical circuit.

To indicate the resistance value of the unit and possibly also its plus or minus tolerance, bands 9 of different color combinations are 20 applied directly to the cylindrical wall 6 of the body.

To attain the objects of this invention by providing an insulating covering which will be transparent so as not to conceal the color code marking and at the same time afford adequate electrical insulation and a degree of protection against moisture, the body of the unit and preferably a substantial portion of its leads 8 are encased in a shell or casing 10 of transparent 25 material having the desired characteristics. This shell or casing 10 may be applied in any of a number of different ways and in Figure 1 the shell is in the form of a tube slipped over the resistor unit with its end portions extending out 30 over the wire leads and twisted as at 11 so as to closely engage the leads and thereby hold it 35 self onto the unit.

The shell or casing may be composed of any 40 one of a number of different substances, preferably some transparent organic film such as "Cellophane", "Pliofilm", a cellulose acetate and modified forms thereof, a cellulose nitrate and modified forms thereof, or any other synthetic resin film.

45 "Cellophane" as is well known is a cellulose product, and "Pliofilm" is a chlorinated rubber product.

The casing or shell may fit the body of the resistor snugly or loosely as shown in Figures 1 50 and 8. With certain types of material, especially "Cellophane", a loose fit is preferable as this material unless specially treated will be electrically conductive after being subjected to humidity, if it is fitted closely to the unit, whereas, if 55

fitted loosely, it is free from this defect. "Pliofilm" on the other hand will not conduct electrically whether it is fitted to the unit tightly or loosely.

Obviously, the casing or shell may be formed in many different ways. In Figure 2, it is built up by winding a ribbon 12 of the desired transparent material continuously and progressively over the wire leads and the body of the unit as shown.

If desired, only the body of the unit is covered with the insulating shell, and in Figures 3, 4, and 5, different ways in which this may be done are shown.

In Figure 3, an insulating and protecting shell is formed by winding a ribbon of the desired material onto the unit.

In Figure 4, a tube 13 slightly longer than the length of the unit is closely fitted to the body. Where this method is employed, it is preferable to use a substance other than "Cellophane" as it entails a tight close fit.

In Figure 5, a sleeve 14 closely fitted to the body as in Figure 4 has its end portions crimped or pressed down against the end walls 7 of the body as at 15 to add to the protection afforded by the covering.

The advantages of the invention are also capable of realization by merely slipping a tube 16 of suitable transparent insulating material over the unit with its end portions projecting out over the wire leads without specific provision for holding the same in place.

In the embodiment of the invention shown in Figure 7, protection against moisture is particularly obtained. In this modification, the protecting shell consists of two telescoped sleeves 17 and 18 pushed onto the unit from opposite ends

thereof and with their adjacent open ends overlapping as at 19. The outer ends of the sleeves are reduced in diameter and have end portions 20 to closely hug the wire leads and thereby insure the greatest protection against the entrance of moisture.

Inasmuch as the end portions 20 frictionally engage the wire leads, no other means need be provided to hold the enclosing shell on the unit and the sleeves need not fit the body closely. However, if desired, the overlapping ends of the sleeves may be fused together or a juncture may be formed therebetween by merely bringing the inner ends of the sleeves into abutting relation and then forming a fused juncture therebetween.

From the foregoing description taken in connection with the accompanying drawing, it will be readily apparent to those skilled in this art that this invention in all of its various modifications provides a simple and efficient manner of electrically insulating fixed resistor units, and that in each instance, the desired insulation is obtained without concealing the color code marking of the unit and without in anywise complicating the design or construction of the unit and at a minimum cost.

What I claim as my invention is:

An insulated electrical resistor comprising: a lumped resistor body; wire leads projecting from opposite ends thereof; and an insulating covering for the body and its leads, said covering being composed of a thin transparent cellulose material and fitting the body loosely so as to provide an air space between the body and the covering, and the ends of the covering being fitted closely to the wire leads.

GEORGE E. MEGOW.
